CLAIM

The ornamental design of a video conference endpoint, as shown and described.

DESCRIPTION

FIG. 1 shows a top back perspective view of the video conference endpoint having a first participant size and embodying the new design;

FIG. 2 shows a top view of the video conference endpoint of FIG. 1;

FIG. 3 shows a right side view of the video conference endpoint of FIG. 1, the left side being a mirror image thereof;

FIG. 4 shows a top back perspective view of the video conference endpoint having a second participant size and embodying the new design;

FIG. 5 shows a top view of the video conference endpoint of FIG. 4; and,

FIG. 6 shows a right side view of the video conference endpoint of FIG. 4, the left side being a mirror image thereof.

The dashed-line showing of environment in the various figures is for illustrative purposes only and forms no part of the claimed design.

The design relates to the appearance of the video conference endpoint. The video conference endpoint comprises a media wall and a table.
